UNITED STATES PATENT OFFICE

2,041,667

MIRROR

John E. Thomas, La Grange, Ill., assignor to
Hooker Glass & Paint Mfg. Co., Chicago, Ill., a
corporation of Illinois

Application April 5, 1935, Serial No. 14,741

3 Claims. (Cl. 88—105)

This invention relates to a mirror. More particularly, the invention relates to a portable type of mirror that is adapted to be positioned on highly polished surfaces, such as tables, buffets, 5 and the like, for decorative purposes.

It has heretofore been customary in the manufacture of table mirrors of this type to glue or cement a layer of felt to the back of the mirror in order to prevent the mirror from scratching the 10 polished surface on which it may be deposited. One of the difficulties of the use of a felt backing is that there is a likelihood of the felt becoming unglued and separated from the mirror. On the other hand, if the felt is secured too 15 strongly to the silvered back of a mirror, there is danger of the silver layer being disrupted due to the pull of the felt on it.

I have now found that a greatly improved table 20 mirror may be made without the use of felt but by uniformly spreading short or powdered fibers over the painted back of the mirror while the paint is still sticky, so as to cause the fibers to adhere to the paint layer and thus afford a soft, 25 non-scratching back for the mirror.

It is therefore an important object of this invention to provide a portable mirror adapted for 30 positioning on highly polished surfaces and the like that has an integrally attached fibrous backing to prevent the scratching of the surfaces on which it may rest.

Other and further important objects of this invention will be apparent from the disclosures in the specification and the accompanying drawing.

This invention (in a preferred form) is illustrated in the drawing and hereinafter more fully described.

On the drawing:

Figure 1 is a top plan view of a table mirror embodying the principles of my invention.

Figure 2 is an enlarged sectional view taken substantially along the line II—II of Fig. 1.

Figure 3 is a fragmentary bottom plan view of the mirror.

As shown on the drawing:

The reference numeral 10 indicates generally a mirror embodying my invention and adapted to be positioned for decorative purposes on some horizontal supporting surface, such as a table or buffet, dresser, or the like. Said mirror 10 com-

50 prises a plate glass 11 having the usual reflecting surface provided by a layer of silver 12. In accordance with usual practice, the layer of silver 12 is protected by a coating of shellac 13 and over that is applied a layer of paint 14.

55 In accordance with the principles of my invention, an outer backing layer of short fibers 15 is applied directly to the paint layer 14 while

the paint is still in a sticky condition. For this purpose a paint having a drying time of about thirty minutes is employed instead of the very quick drying paint that has previously been used, and the short or powdered fibers are sprayed 5 onto the paint surface and caused to adhere thereto to provide a uniform soft mat of fibers. A special type of spray gun is suitably used for applying the short fibers to the paint layer.

The type of fiber that is preferably used is 10 known as "flock." Various types of flock are available on the market, some being derived from cotton, some from wool and some from artificial silks, such as rayon. Any of these may be used 15 satisfactorily.

The advantage of the mirror of my invention is that the fibrous backing of flock is firmly anchored in the paint layer itself, so as to become an integral part thereof. There is thus no danger of the fibrous layer becoming detached, or catching upon some object and pulling the silver surfacing layer away from the plate glass. Furthermore, the fibrous surface is so soft and yielding that it will not scratch even the most highly 20 polished table surface on which the mirror may 25 be positioned.

I am aware that many changes may be made and numerous details of construction may be varied through a wide range without departing from the principles of this invention, and I, 30 therefore, do not purpose limiting the patent granted hereon otherwise than necessitated by the prior art.

I claim as my invention:

1. The combination with a mirror formed of a 35 glass having a silvered surface, of a protective coating therefor comprising a paint-like layer secured to said silvered surface and an external layer consisting of flock particles anchored in said paint-like layer.

40 2. A portable mirror adapted to be positioned on polished surfaces, comprising a plate glass having a silvered surface, a layer of shellac covering said silvered surface, a layer of paint there-over and short fibers anchored in said paint to eliminate the likelihood of said mirror scratching the polished surfaces on which the same may be 45 positioned.

3. A portable mirror adapted to be positioned on polished surfaces, comprising a plate glass 50 having a silvered surface, a layer of paint there-over and cotton flock anchored in said paint to eliminate the likelihood of said mirror scratching the polished surfaces on which the same may be 55 positioned.

JOHN E. THOMAS.
